(57) CLAIM

The ornamental design for an upper for a shoe, as shown and described.

DESCRIPTION

FIG. 1 is a perspective view of an upper for a shoe of the present invention.

FIG. 2 is a left side view thereof.

FIG. 3 is a right side view thereof.

FIG. 4 is a top view thereof.

FIG. 5 is a front view thereof.

FIG. 6 is a rear view thereof; and,

FIG. 7 is a bottom view of the upper for a shoe shown in FIG. 1.

The broken lines on the surface of the upper for a shoe represent stitching and form no part of the claimed design. The broken lines depicting the remainder of the shoe show features that form no part of the claimed design.

1 Claim, 6 Drawing Sheets
